Lacey Lacey, Attorneys

UNITED STATES PATENT OFFICE.

CLAUDE CLEVELAND WHARTENBY, OF UPPER SANDUSKY, OHIO.

BURIAL-VAULT HANDLE.

Application filed July 21, 1921. Serial No. 486,427.

To all whom it may concern:

Be it known that I, CLAUDE C. WHARTENBY, citizen of the United States, residing at Upper Sandusky, in the county of Wyandot and State of Ohio, have invented certain new and useful Improvements in Burial-Vault Handles, of which the following is a specification.

This invention relates to an improved handle for burial vaults and has as one of its principal objects to provide a handle wherein the handle bar employed will be supported for free swinging movement so that said bar will normally gravitate to a position lying alongside the vault while said bar may be freely and easily raised to position spaced from the vault to be grasped.

A further object of the invention is to provide a handle employing a supporting bracket and handle bar arm and wherein the arm will be freely engaged with the bracket so that the arm and bracket may be readily assembled without the use of a pivot pin or other similar element.

And the invention has as a still further object to provide a handle wherein the supporting bracket will be provided with a bar adapted to accommodate a strap for lowering the vault into a grave.

Other and incidental objects will appear hereinafter.

In the drawing:

Figure 1 is a perspective view showing a conventional vault equipped with my improved handle.

Figure 2 is a vertical sectional view on the line 2—2 of Figure 1, looking in the direction of the arrows, and

Figure 3 is a rear elevation showing the supporting bracket employed in detail.

Referring now more particularly to the drawing, I have, for convenience, shown my improved handle in connection with a conventional metal vault 10. A handle is, of course, mounted at each side of the vault but since the handles are identical only one will be described. In carrying the invention into effect, I employ a supporting bracket comprising a body plate 11 from which projects a marginal base flange 12 extended at the upper end edge of the plate to define an oblong base frame 13. Rising from the ends of this frame medially thereof are lugs 14 and extending between said lugs is a strap bar 15 which is preferably circular in cross section, the bar and lugs being integral with

the base frame. As will be observed upon particular reference to Figure 2, the bar is thus spaced above or in front of the base frame so that a strap may be readily looped around the bar. Formed in the body plate 11 medially thereof is a vertically disposed slot 16 opening through the lower edge of the plate and rising from the plate at opposite sides of said slot are flanges 17 connected at their upper ends by an outwardly and downwardly sloping connecting web 18 overhanging the outer vertical edges of said flanges to define a stop shoulder 19. Formed in the flanges from the rear side of the body plate are, as particularly shown in Figure 3, companion substantially semi-circular recesses 20 disposed substantially midway between the ends of the flanges and entering through the inner confronting sides thereof into the slot 16 as well as through the rear face of the body plate.

In conjunction with the supporting member I employ a handle bar arm 21 provided at its outer end with an enlarged eye or sleeve 22 and formed on the arm at its inner end is a disk shaped head 23 from the side faces of which extend oppositely directed lateral trunnions 24. The head 23 is adapted to be freely accommodated between the flanges 17 of the supporting bracket so that the trunnions 24 may thus be engaged in the recesses 20 for pivotally connecting the arm with the bracket, the arm, of course, extending freely through the slot 16. As will thus be seen, this construction provides an arrangement whereby the arm is supported upon the bracket for free swinging movement while the use of pivot pins or other similar elements is eliminated, the arm simply being freely engaged with the bracket and thus adapted to be readily assembled therewith.

As shown in Figure 1, three of the supporting brackets are preferably arranged at equally spaced points upon the adjacent side wall of the vault 10 and extending through the body plates 11 of said brackets and through said wall are fastening devices 25 securing the brackets in position, the base flanges 12 of the brackets seating flat against the wall so that the wall thus serves to close the brackets at their rear sides. Accordingly, said side wall will contact with the arms 21 at their inner ends for holding the trunnions 24 of said arms against displacement from the recesses 20 to

thus prevent the arms from becoming detached while, at the same time, the trunnions may freely rock within said recesses for swingingly supporting the arm. Extending through the sleeves 22 of all of the arms is a handle bar 26 which may be of metal or other approved material and, as will be perceived, the arms will normally gravitate to hang downwardly from the supporting brackets sustaining the handle bar close along the side of the vault. At the same time, the handle bar may be freely swung upwardly so as to be readily grasped. When thus swung upwardly the shoulders 19 of the brackets will coact with the upper edges of the arms 21 for limiting the arms in their upward swinging movement and rigidly sustaining the arms to project laterally from the brackets. As will accordingly be seen, I provide a particularly effective handle for the purpose set forth and a handle which, in providing means to accommodate a strap, will greatly simplify and facilitate the operation of lowering the vault into a grave.

25 Having thus described the invention, what is claimed as new is:

1. A burial vault handle including a supporting bracket comprising a body plate having a slot therein, flanges rising from the plate at opposite sides of the slot, a

web extending between and connecting said flanges, the flanges being formed with recesses opening through the inner side face of the plate, and a handle freely received through said slot and provided with trunnions engaging in said recesses pivotally connecting the handle with the bracket for movement to engage said web to be limited thereby.

2. A burial vault handle including a supporting bracket comprising a body plate provided with a marginal base flange having portions thereof extending beyond the lines of the plate and formed with a cross bar to receive a strap, and a handle carried by the bracket.

3. A burial vault handle including a supporting bracket comprising a body plate having spaced recesses opening through the inner face thereof and provided between said recesses with a slot, there being a web extending at the outer side of the plate to overhang the slot, and an arm freely received through the slot and provided with trunnions journaled in said recesses pivotally connecting the arm with the bracket for upward movement limited by said web.

In testimony whereof I affix my signature.

CLAUDE CLEVELAND WHARTENBY.
